UNITED STATES PATENT OFFICE

EMORY J. GEARHART, OF CLEARFIELD, PENNSYLVANIA

LOOPING MACHINE

Application filed December 23, 1927. Serial No. 242,151.

My invention relates to means for inserting and forming loops of yarn or other material in fabric, as for example in the process of making hook rugs, and has for its primary object to provide a simple, compact and effective device to be operated by hand by which the loops will be quickly formed and firmly held in the fabric and will be automatically spaced and made of equal length throughout.

10 My invention comprises, in its present embodiment, in its entirety, two relatively sliding handles, an eyed needle on one handle to carry the yarn in a loop through the fabric, a loop holder on the other handle, sliding 15 relatively past the needle into the loop to retain the same while the needle is withdrawn from the fabric by the other handle and means whereby as the needle is relatively withdrawn it is thrown a fixed distance in advance of the 20 loop holder and loop, so that as it is again driven through the fabric, it will form the next loop properly spaced from the preceding loop, from which the loop holder is at the same time withdrawn.

25 My invention also comprises specific means for thus throwing the needle forward of the loop holder, consisting preferably of means for pivoting the needle to its handle midway of its length and a spring or other cam member on the handle of the loop holder acting to swing the needle forward on its pivot as it passes the same with the movement of its handle.

30 My invention also comprises other features 35 of construction and arrangement as herein-after described and claimed.

In order that my invention may be fully understood, I shall first describe in detail the mode in which I at present prefer to carry 40 the invention into practice and then particularly point out its various features in the claims.

Reference is to be had to the accompanying drawings, forming part of this application, in which like parts are designated by 45 the same numbers in all the figures.

Figure 1 is a side view partly in section of a looping machine embodying my invention, 50 the needle and loop being shown driven

through a fabric in the process of forming a hook rug, and the loop holder retracted.

Figure 2 is a view similar to Figure 1, showing the loop holder advanced to hold the formed loop in the fabric, and the needle 55 withdrawn and swung forward on its pivot in position to space and form the next loop.

Figure 3 is a cross sectional view on the line 3—3, Figure 2.

In the specific embodiment of my invention thus illustrated, 4 designates the needle holding handle, 5 the eyed needle carried thereby, 6 the loop holder handle and 7 the loop holder carried thereby.

The handles 4 and 6 are made of wood, 65 aluminum or other preferably light material and are in this example made flat with rounded outside edges curved and tapering toward the needle and loop holder ends conveniently to fit the respective hands of the user.

The straight meeting edges of the two handles are, in this case, formed with a longitudinal tongue 8 and groove 9 respectively, so that the handles can slide and will be guided lengthwise on each other, and are also 75 formed with longitudinal guide slots 10 and 11 respectively, the needle handle slot 10 opening at the forward end and the loop holder handle slot 11 opening at the rear end.

In the slots 10, 11, slide the closed ends of 80 keepers 12, 13, respectively, preferably of metal, whose arms embrace and are secured respectively to opposite sides of the opposite handle, so that the two handles will be tied together while guided in their relative length- 85 wise movement.

In the meeting tongue and edge of the needle handle 4 is formed a deep groove 14 in which the needle 5 is seated loosely and is pivoted to swing transversely to and from 90 the loop holder 7, in this instance by a pivot pin 15, entering and loosely fitting one of a longitudinal series of holes 16 in the needle, so that the needle can be adjusted to project more or less from the forward end of its 95 handle and thus vary the length of the loops formed thereby.

The needle holding groove 14 is preferably deepened forward of the needle pivot pin 15 so as to permit the swinging movement of the 100

needle point. The needle 5 is also grooved lengthwise on the outside at its forward portion to its eye to fit and receive the loop holder as hereinafter described.

The loop holder handle 6 is also formed with a longitudinal groove 16 in its forward portion sunk below its slide groove 9, and in the sunken groove 16 at the forward end is received adjustably the shank of the loop holder 7, in this instance by means of set screws 17, passed through a longitudinal slot 18 in the shank into the handle, so that by loosening the screws 17, the loop holding finger 19 of the loop holder, the end 20 of which is notched to retain the yarn, can be projected more or less from the end of its handle to correspond with the greater or less projection of the needle from its handle previously referred to. The loop holding finger 19 is offset from its shank toward the needle so that when the yarn threaded needle is projected into the fabric by projecting its handle, to form the loop, the loop holding finger will be wholly within the corresponding groove of the needle, and as the loop holder is then projected by its handle, the loop holding finger 19 will slide forward in the needle groove through the fabric until its notched end 20 reaches the needle eye and catches and holds the end of the loop.

In the groove 16 of the loop holder handle back of the loop holder is also secured the forward end of a cam spring 21, the rear end of which rises from said groove and has a rear cam 22 which bears against the flat shank 23 of the needle, at the rear of its pivot pin 15, when the needle is projected, so that the point end of the needle is thereby pressed yielding-ly against the loop holder seated therein. As the loop holder is then projected by its handle on the needle, the cam 22 rides along the flat needle shank 23 to its pivot, until, as the loop holder end reaches the needle eye and loop, the cam 22 passes the needle pivot and, as the needle is withdrawn from the fabric, presses the needle point away from the loop holder the distance required properly to space the next loop in the ground fabric from the preceding loop.

As the needle with the yarn is then again projected by its handle through the ground fabric to form the next loop and the loop holder then withdrawn from the preceding loop, the loop holder finger as it leaves the fabric is then thrown by the cam relatively to the needle into the needle groove in position to slide therein through the fabric and into the next loop.

The spring on the cam is preferred because it prevents the needle and loop holder from separating forcibly while both are in the fabric.

The removably stop 25 is by preference screwed into the needle handle across the opening of its longitudinal slot 10 to limit

the movement of the keeper 12 therein and thereby limit the relative movement of the two handles.

It will be seen that the reverse longitudinal movements of the two handles, as well as the movement of the needle with respect to the loop holder, are relative and therefore the means whereby such movements are caused, guided and controlled can be reversed in location and arrangement, without departing from the scope of my invention.

It is also evident that many of the specific features of my invention herein shown and described to illustrate one embodiment thereof may be greatly varied without departing from the boundaries of my invention as defined by the following claims.

I claim as my invention:

1. A looping instrument comprising a handle having a straight edge provided with a groove extending lengthwise thereof, a needle pivoted between its ends in said groove and projecting from one end of said handle, a second handle having a straight edge slideable on the first named straight edge and having a groove alined with the groove in the first named handle, a loop holder fixed in the last named groove and projecting from the end of the second named handle, and a cam in the last named groove in slidable contact with said needle to swing the projecting end thereof toward and from the loop holder when the handles are slid relatively to each other.

2. A looping instrument as specified in claim 1, in which the cam is a leaf spring secured in the last named groove to slide yielding-ly along said needle and on opposite sides of its pivotal connection with the first named handle.

3. A looping instrument as specified in claim 1, in which the needle is provided with a longitudinal series of holes adapted to receive loosely a pivot pin on the first named handle.

In testimony whereof I affix my signature.

EMORY J. GEARHART.
